(57) **CLAIM**

The ornamental design for a fishing scale, as shown and described.

DESCRIPTION

FIG. 1 is a front elevational view of a first embodiment of a fishing scale, showing my new design;

FIG. 2 is a rear elevational view of the embodiment of FIG. 1;

FIG. 3 is a top plan view of the embodiment of FIG. 1;

FIG. 4 is a bottom plan view of the embodiment of FIG. 1;

FIG. 5 is a right side elevational view of the embodiment of FIG. 1;

FIG. 6 is a left side elevational view of the embodiment of FIG. 1;

FIG. 7 is a front perspective view of the embodiment of FIG. 1;

FIG. 8 is a front perspective view of a fishing scale, showing my new design, in an alternate position;

FIG. 9 is a front elevational view of the embodiment of FIG. 8;

FIG. 10 is a rear elevational view of the embodiment of FIG. 8;

FIG. 11 is a right side elevational view of the embodiment of FIG. 8;

FIG. 12 is a left side elevational view of the embodiment of FIG. 8; and,

FIG. 13 is a front elevational view of a second embodiment of a fishing scale, showing my new design.

The top and bottom views of FIGS. 8-12 have been omitted because they are the same as that shown in FIGS. 3 and 4 while the rear, right, top and bottom views of the second embodiment have been omitted because they are the same as that shown in FIGS. 1-7.
